Fig. 10. James Setchfield
by *J. J. Geisler*
Inventors

UNITED STATES PATENT OFFICE.

JAMES SETCHFIELD, OF PORTLAND, OREGON, ASSIGNOR OF ONE-HALF TO THOMAS J. QUIRK, OF PORTLAND, OREGON.

FIREPLACE DAMPER.

Application filed February 26, 1927. Serial No. 171,191.

My invention relates to dampers for a fireplace, and particularly to that form of damper, in which the damper plate is supported on a frame, and is operable from a convenient place outside, and from the front of the fireplace masonry.

The object of my invention is to provide a damper structure which is easy to make, is economical in cost of manufacture; has no projecting parts which in transportation are liable to be broken; which may be arranged in its entirety into a convenient package for transportation at a low rate; and at the same time provides a structure which is strong and durable, easily installed, and dependable in operation.

A further object of my invention is to provide a fireplace damper, operable from the outside of the fireplace from either the center or one side, or from a convenient place within the fireplace.

Another and particular object of my invention is to provide a shiftable guide post in the frame of my damper, this guide post to serve both as a stop for the damper plate, preventing the latter from becoming unseated by a too great movement thereof; the guide post also serving as the guide element for an operating chain attached to the damper plate.

I attain these and incidental objects of my invention in a fireplace damper comprising a frame consisting of a basal web supporting a wall and provided with an interior flange on three sides, and said wall provided with spaced sockets one located at the middle of the frame, the other at one end thereof, and a post adapted to be inserted in either of said sockets. I provide a damper-plate pivotally supported at its ends within the said wall seating on said interior flange of the latter, and means for lifting and lowering the damper-plate. The said damper-plate is provided with a longitudinal rib on its upper face including a stop-lug registering with said wall sockets to bear on the post set therein, and said post is provided with a guide-hole, and a thimble secured to said guide-post and registering with said guide-hole and extending through the brick-facing of the fireplace for receiving an operating-chain attached to said damper-plate.

My invention further embodies certain features hereinafter described with reference to the accompanying drawings.

55

In the drawings:

Fig. 1 shows a perspective view of my fireplace damper, the damper being shown separated from the frame;

Fig. 2 shows a fragmentary perspective view of my damper in larger detail than in Fig. 1, the damper being shown in a closed position in the frame;

Fig. 3 shows a fragmentary perspective view of a corner of the frame in which the damper pintles will be mounted in the wall itself;

Fig. 4 shows a perspective view of my damper with the front portion of the basal web eliminated to adapt my damper to a fireplace which is to be faced with tile and shows a lever provided for operating the damper from outside the fireplace;

Fig. 5 shows in a fragmentary transverse section an end view of the lever for opening and closing the damper;

Fig. 6 shows in a fragmentary longitudinal section the lever for opening and closing the damper;

Fig. 7 shows a plan view of my damper installed in the throat of a fireplace, the upper part of the masonry having been removed; and shows the damper in a closed position, and another operating means provided for opening and closing the damper shown, a portion of the damper and the masonry having been broken away;

Fig. 8 shows a front elevation of a fireplace, a portion of the masonry being broken away disclosing the relative positions of the damper and frame within;

Fig. 9 shows a fragmentary section taken on the line 9—9 of Fig. 7 looking in the direction of the arrows and discloses the opening and closing means employed for operating the damper from outside the fireplace; and

Fig. 10 shows a fragmentary section similarly to Fig. 9 except that the damper plate is in an open position.

100

My damper comprises a frame *a* formed in an elongated trapezoid comprising a basal web *b* provided with integral perpendicular walls *c* and an inwardly sloping wall *d*.

The walls *c* and *d* are spaced from the edge of the basal web *b* and are in height approximately equal to the distance they are spaced from the edges of the basal web.

5 An interior flange *h* is formed at the base of the wall *c* and interior end flanges *i* are formed extending diagonally upward from the base of the wall *c* to the top of the wall *d*. A transverse brace *o* is similarly 10 formed at the center of the frame *a* to provide support for the damper plate and strengthen the frame.

Sockets *m* and *m'* are provided in the longitudinal wall *c*, at the center and one 15 end respectively, and a removable post *l* is provided adapted to fit into either of the sockets *m* or *m'* and is formed with an eye *l'* at its end.

The damper plate *e* is formed with an up- 20 standing longitudinal rib *g* which is highest at its center *p* and one end *p'*, and is adapted to rest on the interior flanges *h* and *i* and on the top of the wall *d* forming a tight closure at all points. Pintles *f* and *f'* 25 provided on each end of the damper plate *e*, are adapted to seat in notches formed in the interior corners of the frame formed by protrusions *j* and *j'*.

The damper plate *e* is also provided with 30 upstanding lugs *q* and *q'* on its outer edge correspondingly spaced as the portions *p* and *p'* of the central rib *g* and are provided with holes *r* and *r'*.

By providing two sockets *m* and *m'* and a 35 post *l* adapted to fit in either one, and corresponding lugs *q* and *q'* and also two raised portions of the rib *g*, I adapt my damper for being operated from the center or the side of the front of the fireplace.

40 Referring now to Fig. 3, I show a modification of my damper in which the pintles *f*, *f'* will be seated in the notches *n* cut in the walls *c*. In this form of construction the damper plate and the pintles *f* and *f'* will be formed somewhat larger.

In Figs. 7, 8 and 9 I show my damper adapted to be operated from the center. A chain *t* is fixed to the lug *q* and adapted to pass over and bear on the portion *p* of the web *g* and is then passed through a thimble *u* which is threaded into the hole *l'* in the post *l*. A keyhole slot is provided in the outer end of the thimble *u* in which the links of chain may be engaged so that the damper may be set in any desired position, and the degree to which it has been opened will be indicated by the number of links which hang outside the thimble.

45 As shown in Figs. 9 and 10, the portions *p* and *p'* of the web *g* first allow the chain *t* to bear thereon and then serve as stops to prevent the damper plate *e* from being unseated by the chain being pulled through the keyhole slot too far.

50 Referring now to Figs. 4, 5 and 6, I show

a modification of my fireplace damper adapted to fireplaces with tile facings instead of pressed brick as shown in the other figures, and when it is not desirable to provide operating means which will extend through the tile facing as shown in Fig. 10.

The pintle *f* is cast somewhat longer and extends through the end wall *c* as shown in Figs. 3, 5 and 6 and a transverse elongate slot 3 is provided in the basal web and a downwardly extending lug 5 is provided with fan-like corrugations 6.

A crank arm 7 which extends through the slot 3 is provided on the end of the pintle *f* and bears against the corrugations 6. The crank arm 7 is offset and extends downward into the opening of the fireplace and may be operated conveniently from there.

55 As best shown in Figs. 4 and 10 the front portion of the basal web will be left off as at 11 in order not to interfere with the backing 8 for the tile facing 9 which may be supported by a suitable angle iron 10.

I claim:

1. A fireplace damper comprising, a frame 60 consisting of a basal web supporting a wall, said wall provided with a socket, a post adapted to be inserted in said socket, and a damper plate pivotally supported at its ends within the said wall.

2. A fireplace damper comprising, a frame 65 consisting of a basal web supporting a wall, said wall provided with a socket, a post adapted to be inserted in said socket, a damper-plate pivotally supported at its ends within the said wall, and means for lifting and lowering the damper-plate.

3. A fireplace damper comprising, a frame 70 consisting of a basal web supporting a wall, said wall provided with a socket, a post adapted to be inserted in said socket, a damper-plate pivotally supported at its ends within the said wall, means for lifting and lowering the damper-plate, and said damper-plate provided with a stop-lug registering 75 with said wall socket to bear on the post set therein.

4. A fireplace damper comprising, a frame 80 consisting of a basal web supporting a wall, said wall provided with a socket, a post adapted to be inserted in said socket, a damper-plate pivotally supported at its ends within the said wall, means for lifting and lowering the damper-plate, said damper-plate provided with a stop-lug registering 85 with said wall socket to bear on the post set therein, and said post provided with a guide-hole for receiving an operating-chain attached to said damper-plate.

5. A fireplace damper comprising, a frame 90 consisting of a basal web supporting a wall provided with an interior flange on three sides, said wall provided with a socket, a post adapted to be inserted in said socket, a damper-plate pivotally supported at its 95

ends within the said wall and seating on said interior flange of the latter, and means for lifting and lowering the damper-plate.

6. A fireplace damper comprising, a frame consisting of a basal web supporting a wall provided with an interior flange on three sides, said wall provided with a socket, a post adapted to be inserted in said socket, a damper-plate pivotally supported 5 at its ends within the said wall and seating on said interior flange of the latter, means for lifting and lowering the damper-plate, and said damper-plate provided with a longitudinal rib on its upper face including a stop-lug registering with said wall socket, and said post provided with a guide-hole, a thimble secured to said guide post and registering 30 with said guide hole and extending through the brick-facing of the fire place for receiving an operating-chain attached to said damper-plate.

10. A fireplace damper comprising, a frame consisting of a basal web supporting a wall provided with an interior flange on three sides, said wall provided with a socket, a post adapted to be inserted in said socket, a damper-plate pivotally supported at its ends within the said wall and seating on 15 said interior flange of the latter, means for lifting and lowering the damper-plate, said 20 socket to bear on the post set therein.

7. A fireplace damper comprising, a frame consisting of a basal web supporting a wall provided with an interior flange on three sides, said wall provided with a socket, a post adapted to be inserted in said socket, a damper-plate pivotally supported at its ends within the said wall and seating on 25 said interior flange of the latter, means for lifting and lowering the damper-plate, said

damper-plate provided with a longitudinal rib on its upper face including a stop-lug registering with said wall socket, and said post provided with a guide-hole, a thimble secured to said guide post and registering 30 with said guide hole and extending through the brick-facing of the fire place for receiving an operating-chain attached to said damper-plate.

8. A fire place damper comprising a frame consisting of a basal web supporting a wall, said wall provided with spaced sockets, one located at the middle of the frame, the other at one end thereof, a post adapted to be inserted in either of said 40 sockets, a damper-plate pivotally supported at its ends within the said wall, means for lifting and lowering the damper-plate, said damper-plate provided with a longitudinal rib on its upper face including a stop-lug 45 registering with said wall sockets to bear on the post set therein, and said post provided with a guide-hole for receiving an operating-chain attached to said damper-plate.

JAMES SETCHFIELD.
